UNITED STATES PATENT OFFICE.

LATHAM BRIGHTMAN, OF CLEVELAND, OHIO.

MACHINE FOR DRAWING METAL BARS.

SPECIFICATION forming part of Letters Patent No. 268,456, dated December 5, 1882.

Application filed March 17, 1882. (No model.)

To all whom it may concern:

Be it known that I, LATHAM BRIGHTMAN, of Cleveland, in the county of Cuyahoga and State of Ohio, have invented certain new and 5 useful Improvements in Machines for Drawing Metal Bars; and I do hereby declare the following to be a full, clear, and exact description of the invention, such as will enable others skilled in the art to which it pertains to 10 make and use the same.

My invention relates to machines for drawing metal bars; and it consists in the peculiar construction of the same, as will be hereinafter fully set forth and claimed.

15 In the drawings, Figure 1 is a side elevation of a machine embodying my invention. Fig. 2 is a plan view of my improved drawing-die; and Fig. 3 is a vertical section taken through the same.

20 A is the frame of my machine, in which are journaled the chain-wheels B B', which engage with and operate to drive the chain C.

D is my clamping device, which is mounted on wheels D', and is shown mostly in dotted lines, Fig. 1. This clamping device is composed of an upper and lower jaw, a and b, the upper jaw, a, being pivoted to the lower jaw, b, near its forward end, and provided at its rear end with a set-screw, c, the lower end of 25 30 35 said set-screw c resting on a seat, d, formed on the lower jaw, b, and the thread of said set-screw (not shown) engaging with a female screw-thread in the upper jaw, a. Thus when the set-screw c is turned in one direction it acts to close the jaws a and b, and when turned in the opposite direction it acts to open the jaws for the purpose of clamping or releasing the bar.

To allow the clamping device to more securely hold the end of the bar to be drawn, I first reduce the diameter of the end of the bar so as to allow of its passing through the die far enough to be grasped, and then again reduce the bar a short distance from the end, 40 45 forming a shoulder, e, and head f. The grasping end of the clamping device D is made so as to conform to the shape of this end, and by engaging with it to hold it tightly, and thus prevent it from slipping out of said clamping device D.

50 My preferred manner of shaping the end of the bar is shown in Fig. 3 of the drawings.

E is a hook, which is pivotally attached to the rear end of the clamping device, and is 55 adapted to engage with the links of the chain

C. This hook E is operated by means of a bell-crank lever, F, and weighted lever G, as will be hereinafter set forth.

H is the die-holder of my machine.

I is my drawing-die, which is preferably 60 made of cast metal, (iron or steel,) and provided, as is usual, with a tapering hole, I'.

Surrounding my die I is a band of wrought-metal, J, which is preferably shrunk on the same. This band J acts to strengthen the said 65 die I, and prevent it from breaking apart by the force of the metal as it (the metal) is being drawn through the said die.

The operation of my device is as follows: Power is applied to the wheels B and B' in 70 such a manner as to cause them to move the chain C in the direction of the arrow, Fig. 1, the hook E being held out of contact with the said chain C by means of the weighted lever G, which is secured to the bell-crank lever F. The 75 bar after being reduced, as hereinbefore described, is passed through the die I, which is secured in the die-holder H. The jaws of the clamping device D are then caused to grasp the prepared end of the bar, being operated by 80 means of the set-screw c. The hook E is now caused to engage with the chain, (by hooking into one of the links,) which pulls the clamping device D in the direction of the arrow, which in turn acts to pull the bar through the 85 die I, and thereby reduce it. When the end of the bar has been reached and passed through the die, the strain being removed from the hook E, the weighted lever G acts to disengage it from the chain C, and the clamping device 90 stops and the bar may be removed.

What I claim is—

1. In a machine for drawing metal bars, the combination, with a clamping device, of a hook for engaging with the chain, and a weighted 95 lever attached to said hook for automatically disengaging the hook from the chain when the strain is removed, substantially as and for the purpose shown and described.

2. The combination, with the chain, the carriage D, and hook E, of the clamping-jaws a b, set-screws c, and weighted lever, substantially 100 as set forth.

In testimony whereof I have signed my name to this specification in the presence of two subscribing witnesses.

LATHAM BRIGHTMAN.
